UNITED STATES PATENT OFFICE.

HENRY SIMS, OF ERIE, PENNSYLVANIA.

COMBINED WATER-HEATER AND GARBAGE-BURNER.

1,081,337.

Specification of Letters Patent. Patented Dec. 16, 1913.

Application filed February 13, 1913. Serial No. 748,136.

To all whom it may concern:

Be it known that I, HENRY SIMS, a citizen of the United States, residing at Erie, in the county of Erie and State of Pennsylvania, have invented certain new and useful Improvements in Combined Water-Heaters and Garbage-Burners; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to devices for heating water and consuming garbage; such devices being so constructed and arranged that the heating of the water and burning of the garbage is effected by the use of fuel, usually coal, in the fire-box; and the object of this invention is to provide a garbage supporting grate in the fire-box, so located therein that the front end thereof is secured to the front end of the fire-box, somewhat above the fire-door thereof, and from that point the garbage grate inclines rearwardly and downwardly to the rear end of the fire-box, where a door is provided, whereby any unconsumed part of the garbage can be removed.

The features of my invention are herein-after fully set forth and described, and illustrated in the accompanying drawings, in which:

Figure 1, is a vertical, longitudinal, central section of my combined water-heater and garbage-burner. Fig. 2, is a vertical section of the same, on the line X—X in Fig. 1.

In the construction of my combined water-heater and garbage-burner, I preferably make the outer portion thereof, of two wrought metal shells, A, and A'; the shell A, within the shell A', and spaced therefrom so as to leave a water containing chamber C, between said shells, extending from the base B thereof, entirely around the sides, end and top thereof. In the base of the chamber inclosed by the inside shell A, I place grate-bars A², the rear and front ends of which rest upon ledges a a, on the base of the inside shell A; the entire structure above described, being preferably supported on a convenient base B, provided at its front end by an ash door B'.

In the front end of the structure, somewhat above the grate-bars A², I make a fuel-door opening A³, which is provided with a door A⁴. In the top of the structure I secure a smoke-flue C', and communicating with the water space C, between the shells A A', I make an opening a', in the lower part of the outer shell A', to which a water supply pipe (not shown) may be connected, and I also make a discharge opening a², in the top of the outer shell A', for the discharge of hot water from the chamber C.

In the front of the inside shell A, at a point above the fuel-door opening A³, I secure a series of tubes D, which tubes extend therefrom rearwardly and downwardly, to a point in the rear of the inner shell A, and are secured therein, so that both the front and rear ends of these tubes communicate with the water space C, between the shells, A A'. The tubes D, are so spaced apart as to form a suitable grate upon which the garbage is to be burned, and being connected at their ends with the water space C, the water therein circulates therethrough much more rapidly than it does through horizontal tubes, and thereby the heating effectiveness thereof is materially increased.

In the front end of the structure, somewhat above the front ends of the tubes D, I make a garbage receiving opening E, provided with a door E', and in the rear end of the structure, somewhat above the lower and rear ends of the tubes D, I make an opening F, provided with a door F', through which any unconsumed portions of the garbage can be removed. Through the outer shell A', opposite the front and rear ends of said tubes, I make openings which are normally closed by screw plugs a³ a³, which may be removed when it is necessary to clean the tubes D. This tubular garbage-grate, it will be observed, inclines downward from the front to the rear of the structure. The object of this construction is to provide means whereby the products of combustion, from the fuel-burning chamber G, can escape into the chamber above the garbage-grate, as when a lot of wet garbage is placed upon the garbage-grate, it normally is deposited upon the inclined portion thereof, leaving the upper end of the grate with little or none of the garbage resting thereon, and therefore leaving a free

passage from the fire-chamber between the upper ends of the tubes D, forming said grate, and as the garbage is consumed, any unconsumed part thereof, works down the inclined garbage-grate to the opening F, through which it can be readily removed.

Having described my invention so as to enable others to construct and use the same, what I claim as new and desire to secure by

10 Letters Patent is:

1. In a combined water-heater and garbage-burner, the combination of two shells forming a heating chamber, one shell so arranged within the other as to form a water-chamber between them; a fuel-grate in the bottom of the heating-chamber, a door to supply fuel to said grate, a garbage-grate above the fuel-burning grate having parallel bars, extending from above the fuel door in the front wall of the heating-chamber at an inclination downwardly to a point in the rear wall of the heating-chamber slightly above the rear end of the fuel-grate, and communicating at their front and rear ends with the water-chamber, and forming a garbage-grate in said heating-chamber adapted to permit garbage placed thereon to move downwardly so as to insure a free passage through the upper end of said garbage grate for the products of combustion from the fuel grate, doors in the front and rear of the heating-chamber above the ends of the 25 garbage-grate, and a smoke exit opening in the top of the heating-chamber, substantially as set forth.
2. In a combined water-heater and gar-

bage-burner, the combination of two shells forming a heating-chamber, one shell so arranged within the other as to form a water-chamber between them, a fuel-grate in the bottom of the heating chamber, a door to supply fuel to said grate, a series of parallel water-tubes above the fuel-burning grate, 35 extending from above the fuel door in the front wall of the heating-chamber at an inclination downwardly to a point in the rear wall of the heating-chamber slightly above the rear end of the fuel-grate, and communicating at their front and rear ends with the water-chamber, and forming a garbage-grate in said heating-chamber adapted to permit garbage placed thereon to move 40 downwardly so as to insure a free passage through the upper end of said garbage grate for the products of combustion from the fuel grate, doors in the front and rear ends of the heating-chamber above the ends of the garbage-grate, water inlet and outlet 45 openings in the outer shell of the heating-chamber, and a smoke exit from the top of the heating-chamber, substantially as set forth.

In testimony whereof I affix my signature, in presence of two witnesses.

HENRY SIMS.
